UNITED STATES PATENT OFFICE.

HENRY E. VEIT, OF CHICAGO, ILLINOIS.

LOOSE-LEAF BINDER.

SPECIFICATION forming part of Letters Patent No. 729,979, dated June 2, 1903.

Application filed July 23, 1901. Serial No. 69,384. (No model.)

To all whom it may concern:

Be it known that I, HENRY E. VEIT, a citizen of the United States, residing at Chicago, in the county of Cook and State of Illinois, ⁵ have invented new and useful Improvements in Loose-Leaf Binders, of which the following is a specification.

My invention relates particularly to binders for loose-leaf albums and the like; and ¹⁰ my primary object is to provide an improved binder of this character adjustable in thickness to suit the book contents and so arranged that the book will always open flat and remain open unweighted, said binder being particularly adapted to the heavy class of work suggested.

My invention is illustrated in the preferred form in the accompanying drawings, in which—

²⁰ Figure 1 represents a broken inner view, partly in section, of the closed end of the binder; and Fig. 2 a broken section taken as illustrated at line 2 of Fig. 1.

In the preferred construction there are employed ²⁵ two separable cover-sections, two clamping-bars, having hinged connection at their rear or lower edges with the rear or binding edges of said cover-sections, extensible binding-posts connecting said clamping-bars, extensible end clamping-posts detachably connected with the ends of said clamping-bars, and a spring-equipped follower ³⁰ removably confined between said clamping-bars and serving to hold the book contents firmly in place before the binder is filled.

The preferred construction is as follows: ³⁵ A A' represent cover-sections, the section A being provided at its hinged end with a tongue or extension a, which telescopes with a suitable pocket at the base or hinged end of the section A' in the manner shown in my existing Patent No. 606,434, June 28, 1898; B B', hollow metallic clamping-bars secured by hinges b to the rear or binding portions ⁴⁰ of the sections A A'; B², telescopic binding-posts, the large or tubular portions of which are carried by the bar B' and the smaller portions of which are carried by the bar B; C C, spring-equipped followers confined between ⁴⁵ the bars B B' and serving to hold the sheets c firmly against one of said clamping-bars, and D detachable end binding-posts con-

nected with the ends of the clamping-bars B B'. The hinges b are firmly secured to the cover-section A A' by rivets b', which pass through perforations in the hinged leaves b² and cover-sections A A', and to the rear side portions of the clamping-bars B B' by brazing or otherwise securing thereto the hinged leaves b³. The followers C comprise bars or ⁵⁵ members d, connected by extensible posts d', about which are coiled springs d², and connected also by a chain d³, which limits their separation. As illustrated in Fig. 2, the members d are cut away at the points d⁴ at their ⁶⁰ extremities to permit them to receive the posts B². The end posts D comprise, preferably, telescopically-connected members f f'. The member f comprises a tubular portion f², a hollow bar-form part f³ parallel and adjacent thereto, an arm f⁴ at right angles to the parts f² f³ and which serves to enter the hollow bar B, and a flatspring f⁵, secured to the part f⁴ at its inner end and having near its ⁶⁵ outer end a perforation which receives a point f⁶, with which the adjacent inner wall of the hollow bar B is provided. The part f' comprises a post f⁷, a parallel bar f⁸, an arm f⁹ at right angles thereto, and a spring f¹⁰, provided with a perforation receiving a stud f¹¹ ⁷⁰ on the adjacent inner wall of the clamping-bar B'. The parts f⁷ f⁸ move telescopically in the parts f² f³ and are adjustably connected therewith by a set-screw f¹². Any suitable means may be provided, if desired, to prevent the ⁷⁵ part f' from becoming entirely separated from the part f.

In Fig. 2 I have shown the leaves c provided at their rear edges with notches, recesses, or perforations g for receiving the ⁸⁰ posts B² and at their top and bottom edges with notches g' for receiving the members f³ f⁸ of the end posts D.

The operation will be readily understood from the foregoing description. The parts of ⁸⁵ the binder being assembled substantially as shown in Fig. 1, but with the follower C removed, any desired number of sheets may be placed in the binder, the thickness of the book being regulated by the screws f¹². When ⁹⁰ the desired number of sheets are in place, assuming the binder not to be filled, the follower C may be pressed into place to firmly press the sheets against one of the clamping-

bars of the binder. When the binder is filled, the follower is of course no longer in use. As will be readily understood from the sectional portion of Fig. 1 the end binding-posts B may be readily removed from the clamping-bars, to which they are secured, by pressing the springs $f^5 f^{10}$ together by means of the thumb and finger to disengage the perforations of said springs from the studs $f^6 f^{11}$. This permits the leaves to be readily removed. When it is desired to increase the capacity of the binder, the screws f^{12} may be loosened and the binder-sections separated, the telescopic connection of the tongue a with one of the cover-sections permitting this action.

The leaves c may be of cardboard and have suitable recesses for receiving pictures when the binder is to be used as an album.

Changes in details of construction within the spirit of my invention may be made. Hence no limitation is to be understood from the foregoing detailed description except as shall appear from the appended claims.

What I claim as new, and desire to secure by Letters Patent, is—

1. In a binder of the character described, the combination of two suitable cover-sections, two clamping-bars pivotally connected with the rear edges thereof, and extensible end binding-posts detachably connected with the ends of both said clamping-bars.
2. In a binder of the character described, the combination of two suitable cover-sections, two clamping-bars hinged to said cover-sections, extensible intermediate binding-posts connected with said clamping-bars, and extensible end binding-posts detachably connected with both said clamping-bars.

3. In a binder of the character described, the combination of two suitable cover-sections, two clamping-bars hinged thereto and having hollow ends, and extensible binding-posts connected with said hollow ends and provided with inwardly-extending arms projecting into and detachably connected with said hollow ends.

4. In a binder of the character described, the combination of two suitable cover-sections, two clamping-bars hinged thereto, and extensible end binding-posts detachably connected with said clamping-bars and which comprise two telescoping members, and means for firmly securing said telescoping members together in any desired position.

5. In a binder of the character described, the combination of two suitable cover-sections, two clamping-bars hinged thereto, extensible intermediate binding-posts connecting said clamping-bars, and extensible end binding-posts detachably connected with the ends of both said clamping-bars.

6. In a binder of the character described, the combination of two suitable cover-sections, two clamping-bars connected therewith, extensible posts connecting said clamping-bars, and a spring-equipped follower, comprising two bars joined by extensible posts, springs tending to separate said bars, and means for limiting the separation of said bars, said bars being provided with recesses for receiving a clamping-bar binding-post.

HENRY E. VEIT.

In presence of—

ALBERT D. BACCI,
WM. B. DAVIES.
